UNITED STATES PATENT OFFICE.

FRED E. FARLEY, OF GREENFIELD, MASSACHUSETTS, ASSIGNOR TO GOODELL-PRATT COMPANY, OF GREENFIELD, MASSACHUSETTS, A CORPORATION OF MASSACHUSETTS.

RATCHET MECHANISM.

Application filed June 21, 1923. Serial No. 646,774.

To all whom it may concern:

Be it known that I, FRED E. FARLEY, a citizen of the United States of America, residing at Greenfield, Franklin County, Massachusetts, have invented new and useful Improvements in Ratchet Mechanism, of which the following is a specification.

This invention relates to improvements in ratchet mechanism, the principal object of the invention being to provide a mechanism of this character which is simple in construction and strong and durable in operation.

A further object of the invention is to provide a ratchet mechanism in which the parts are held in position in such a manner that when the device is being disassembled every part will remain in place until manually removed, thereby eliminating liability of loss of any of the parts.

With the foregoing and other objects in view, which will appear as the description proceeds, the invention consists in the novel features of construction and combination of parts, which will be more fully described hereinafter and particularly pointed out in the claim.

In the drawings accompanying and forming part of this specification,

Fig. 1 is a partly sectional side view of a ratchet mechanism embodying the features of the present invention;

Fig. 2 is a plan view of the cam disk showing the form of cam for operating the pawls;

Fig. 3 is a transverse section taken on the line 3—3 of Fig. 1, showing the shaft-operating handle broken away;

Fig. 4 is a fragmentary end view on an enlarged scale, illustrating the cam end of the shaft with one of the pawls in its inoperative positions, the cam being shown in dotted lines;

Fig. 5 is a fragmentary and partly sectional view of the same end of the shaft illustrating both pawls in their ratchet-engaging position, and showing the means for retaining them in such position; and

Fig. 6 is a view similar to Fig. 4, but illustrating the opposite pawl in inoperative position.

The same characters of reference designate the same parts in the different figures of the drawings.

Referring to the drawings, 2 designates a spindle which is provided in a portion of its

length with a pair of recesses 3 disposed at opposite sides of a line passing transversely through the axial center of the shaft in one direction, but both on the same side of a line passing through said axial center in a direction perpendicular to said first line. The side walls of the recesses 3 extend parallel with the shaft, while the bottom walls as illustrated herein are of step formation, that is to say, they comprise two horizontal portions at different levels and an inclined portion uniting said horizontal portions. If desired, however, the inclined portion might be continued from the lower horizontal portion to the opposite side wall of the recess, without the formation of a second horizontal portion, this latter portion being formed merely for convenience in machining.

Mounted in the recesses 3 are a pair of pawl-forming strips 4, which are of less thickness than the width of the recesses and are adapted to be rocked laterally of the shaft on one of their side edges parallel with the axis of the shaft, from one side of their respective recesses toward the other. The pawls are of such width that when in their operative position adjacent to and parallel with the outer side walls of the recesses, the upper outer corners of the pawls project out beyond the periphery of the shaft, while when rocked to inoperative position the pawls lie wholly within said periphery. For normally retaining the pawls in their operative position, a spring 5 is provided, shown herein as a helical spring seated in a circumferential recess or groove formed in the shaft. The opposite ends of the spring are bent to form hooks for engagement with the longitudinal upper edges of the pawls, each of said pawls being provided with a recess or notch 6 in which the hooked end of the spring rests, thereby to prevent longitudinal shifting of the pawl. The shaft is provided with a second circumferential groove adjacent to the inner ends of the pawls, in which groove is secured a spring wire ring 7, which bears against the ends of the pawls, and assists in retaining them against longitudinal movement.

A gear wheel 8 is mounted on the shaft for free rotation thereon, said gear wheel being shown herein as provided with two concentric sets of teeth 9 and 10 for transmitting motion from the shaft at different speeds. The hub 11 of the gear wheel is

2
provided interiorly thereof with a series of notches 12 forming ratchet teeth for cooperation with the pawls hereinbefore described, the ends of the teeth being flattened to provide a bearing surface for the shaft. The shaft is provided with a crank handle or lever 13, said handle having formed integral therewith a collar 14 adapted to snugly fit the shaft and be secured thereon by means of a pin or key passing through a transverse opening 15 in the collar and engaging a flat portion 16 formed in the periphery of the shaft in the well known manner. The collar is provided with a pair of notches 17 to receive the upper outer corners of the pawls when in their operative position.

For rocking the pawls into their inoperative position, a cam disc 18 is provided, said disc being secured on the end of the shaft for rotation relatively thereto by means of a stud 19. The disc is provided at the side thereof adjacent to the end of the shaft with a cam member 20 having an opening of the form shown in Fig. 2. The pawls extend beyond the end of the shaft a distance equal to the depth of said opening, as shown in Fig. 1, so that when the disc is secured on the shaft the ends of the pawls project into the cam opening in the disc.

30 The operation of the device is as follows: When the cam is in its central position, both of the pawls are in their operative position parallel with the side walls of their recesses. This position of the parts is illustrated in 35 Fig. 5, wherein the cam opening is shown in dotted lines. In this position of the pawls there is no ratchet action. That is to say, the shaft and gear are locked for rotation together in both directions. Upon rotation 40 of the cam disc toward the left from the position shown in Fig. 5, the cam projection 21 at the right of the shaft comes into contact with the upper edge of the right-hand pawl and rocks the pawl inwardly against 45 the tension of the spring, throwing it into the position shown in Fig. 4. When the pawl has reached the limit of its inward motion, the cam portion 22 will have come into contact with the outer side of the pawl and 50 will thus retain it in inoperative position. The disc is then at one of its extreme positions, and the pawl 4 at the left-hand side of the shaft will slide over the ratchet teeth when the shaft is rotated toward the left, 55 but will engage said teeth when rotated toward the right, so as to lock the gear to the

shaft for rotation therewith. If the disc is then rotated to its opposite extreme position, the cam portions 21 and 22 at the left will act on the left-hand pawl in the same 60 manner as above described with reference to the right-hand pawl, thus throwing said left-hand pawl into inoperative position as shown in Fig. 6, the right-hand pawl having in the meantime returned to its operative 65 position under the action of the spring 5, so that if the shaft is now rotated toward the right the pawl will slide over the ratchet teeth, but upon rotation of the shaft toward the left the pawl will engage said teeth and 70 thus lock the gear to the shaft for rotation therewith. As hereinbefore stated, when the cam is in its central or neutral position, both pawls engage the ratchet teeth so that the gear is rotated with the shaft in both 75 directions. The outer face of the disc may be marked with appropriate letters, as indicated in dotted lines in Fig. 2, to designate the three positions of the disc.

80 While I have described in detail the device herein illustrated, it is to be understood that I do not thereby confine my invention to the precise features of construction shown, as I am aware that many mechanical changes and modifications may be made 85 therein without departing from the spirit and scope of the claim appended hereto.

Having thus described my invention, what I claim is:

90 A ratchet mechanism, comprising a shaft provided with a pair of longitudinally extending recesses, a gear wheel mounted for rotation on said shaft and having a hub provided with internal ratchet teeth, a rockable pawl in each of said recesses and adapted 95 to project beyond the periphery of said shaft into engagement with said ratchet teeth thereby to lock the shaft and gear wheel for rotation together, said shaft having a circumferential recess, a spring disposed in said recess engaging both of said pawls to retain them in operative position, a rotatable cam-disc, and a pair of cam members for each of said pawls, one of said members being adapted to rock its pawl 100 against the tension of said spring out of engagement with said ratchet teeth, and the other of said members being adapted to lock said pawl in its disengaged position.

11 In testimony whereof I have signed my name to this specification.

FRED E. FARLEY.
